CIRCUIT BREAKER

Oliver S. Jennings, Pittsburgh, Pa., assignor to
Westinghouse Electric & Manufacturing Com-
pany, East Pittsburgh, Pa., a corporation of
Pennsylvania

Application December 17, 1936, Serial No. 116,324
Renewed July 20, 1939

35 Claims. (Cl. 200—116)

My invention relates to circuit breakers in general, and more particularly, to circuit breakers of the type used for controlling lighting and industrial power feeder circuits.

5 For this type of service, it is particularly desirable to have a circuit breaker which embodies an operating mechanism for moving the contact controlling arm to open and to closed circuit position with a snap action in order to insure quick
10 make and break action. The contact controlling arm or switch member of the breaker must also be trip-free of the operating handle, i. e., the switch arm must be capable of moving to open circuit position in response to predetermined
15 overload conditions, irrespective of the position of the control handle. As opposed to these structural and operational requirements, a commercially successful circuit breaker must be moderate in price. Heretofore, manufacturers of these
20 devices have endeavored to produce circuit breakers as cheaply as possible, consistent with good quality and ability to meet the requirements. The best of the prior art devices, however, were more costly than would be desired.

25 It is also desirable that the circuit breaker be constructed so that it can be easily and cheaply assembled by slidably positioning the parts in recesses in the housing.

It is, accordingly, one of the principal objects
30 of my invention to provide a simple, efficient and inexpensive circuit breaker which will satisfactorily meet the above-mentioned requirements.

Another object of my invention is to provide an improved circuit breaker structure that utilizes 35 a considerably less number of parts than has heretofore been considered necessary for breakers of the same general type.

Another object of my invention is to provide a simpler operating mechanism and trip arrangement
40 for a circuit breaker which requires fewer parts than devices of the same general type heretofore known or used.

Another object of my invention is to provide an improved circuit breaker embodying a simple
45 operating mechanism for producing quick make-and-break action and embodying a simple trip arrangement for tripping the breaker open in response to predetermined overload conditions in which the switch member of the circuit breaker
50 is trip-free of the operating handle.

Another object of my invention is to provide an improved circuit breaker structure in which the parts thereof are capable of quick and easy assembly or disassembly for adjustment, repair or
55 replacement purposes.

The novel features that I consider characteristic of my invention are set forth in particular in the appended claims. The invention itself, however, both as to structure and operation, together with additional objects and advantages
5 thereof, will best be understood from the following detailed description of several embodiments thereof when read in connection with the accompanying drawings, in which:

Figure 1 is a vertical sectional view of a circuit
10 breaker embodying the features of my invention,
the parts thereof being shown in the closed cir-
cuit position;

Fig. 2 is a horizontal sectional view of the cir-
15 cuit breaker shown in Fig. 1, taken on the line
II—II thereof and looking in the direction of
the arrows;

Fig. 3 is a vertical sectional view of the circuit
breaker, similar to Fig. 1, but with the parts of
20 the breaker shown in the tripped position;

Fig. 4 is a side elevational view of a modified
25 form of the circuit breaker unit, the parts thereof
of being shown in the closed circuit position;
and

Fig. 5 is an end elevational view of a group of
25 the circuit breaker units similar to the one shown
in Fig. 4 assembled to form a multi-pole breaker
or load center device.

Referring to Figs. 1 and 2 of the drawings, the
circuit breaker illustrated comprises, in general,
30 a base 7, a cover 9, end terminals 11 and 13, a
stationary or rupture contact 15, a cooperating
movable switch arm 17, an operating mechanism
indicated generally at 19, and a bimetallic trip
35 element 21.

The base 7 is of molded insulating material and
is formed to provide a chamber for the switch
arm and for a part of the operating mechanism.
The cover 9 is also of molded insulating mate-
rial and has a chamber portion for cooperating
40 with the chamber portion of the base 7. The
cover 9 is provided with a transverse partition
member 23 for dividing the casing formed by the
cover 9 and base 7 into an arc chamber 25 and an
operating chamber 27. The side walls of the base
45 and cover are provided with oppositely disposed
aligned grooves 29 for a purpose which will be
hereinafter described.

The left-hand end terminal 11 comprises a
flat copper strip having an off-set portion 31, to
50 the end of which is secured a stationary contact
15. The terminal strip 11 is adapted to be se-
cured to the base 7 by means of a screw 33. The
outer end of the terminal strip 11 is provided with
55 a threaded opening for the reception of a terminal

screw 35 for connecting the terminal to an external electric circuit. The right-hand end terminal 13 comprises a flat angular strip of conducting material which has one end portion secured to the base 7 by means of a terminal screw 37 and a nut 39.

The switch arm 17 has a channel-shaped portion 18 the sides of which are provided with openings for mounting the same on a pivot pin 41. The left-hand end of the switch arm 17 has a movable contact 43 secured thereto in any suitable manner, as for example, by brazing or soldering. The right-hand end of the switch arm 17 has a deep notch 45 formed therein to provide a resilient end portion 47.

The operating means for the switch arm comprises, in general, a channel-shaped actuating member 49, a toggle type operating handle 51 and an overcenter spring device 53. The actuating member 49 is channel-shaped in cross-section and has depending leg portions 55 each of which is provided with an opening for mounting the channel-shaped actuating member on the pivot pin 41. The rearward portion of the switch arm 17 is adapted to normally lie in the channel section of the actuating member 49 between the legs 55 thereof.

The switch arm 17 is normally connected to the actuating member 49 for movement therewith by means of a bimetallic trip element 21. The trip element 21 comprises a U-shaped strip of bimetallic material, one leg of which is secured to the resilient end portion 47 of the switch arm 17 by any suitable means, as for example, by soldering. The body portion of the bimetallic strip projects through a slot 57 provided therefor in the top of the actuating member 49, and the free end 59 of the strip is disposed in overlapping engagement with a cross piece 61 of the actuating member formed by the slot 57. The free end of the bimetallic strip 21 is electrically connected to the end terminal 13 by means of a flexible shunt conductor 63. It will thus be seen that under normal conditions, the bimetallic trip element 21 serves to connect the switch member 17 to the actuating member 49 for movement therewith. The passage of a predetermined value of overload current through the switch arm and bimetallic element 21 which is connected in circuit therewith, causes the end of the bimetallic element to flex to the right to effect disconnection of the switch arm 17 from the actuating member 49 to effect automatic opening of the circuit in a manner which will be described in connection with the operation of the breaker.

The switch arm 17 is biased to open circuit position by means of a coil spring 65. The spring 65 is coiled about the pivot pin 41 and one end thereof engages against the base 7 while the other end engages the underside of the switch arm 17.

The operating handle 51 is formed of molded insulating material and is provided with a pivot pin 67, which is of slightly greater length than the width of the operating handle. The handle 51 has a portion 69 which projects through an opening 71 formed in the top of the cover 9, and with a depending portion 73. An end support 75 for the overcenter spring device 53 is pivotally connected to the depending portion 73 of the operating handle 51 by means of a pivot pin 77. The overcenter spring device 53 consists of a pair of concentric coil springs 79 and 81. The upper ends of the springs engage the end support 75 while the lower ends thereof engage an

end support 83 which has a notch 85 formed therein for pivotally mounting the same on a cross-piece 87 of the actuating member 49.

The bottoms of the grooves 29 in the side walls of the base 7 provide a bearing support for the ends of the pivot pin 41, while the top ends of the grooves 29 in the side walls of the cover member 9 provide bearing surfaces for the ends of the pivot pins 67 of the operating handle 51. The pivot pins 67 and 41 are thus disposed in vertical alignment and the coil springs 79 and 81 are compressively stressed between the end supports 83 and 75. The depending portion 73 of the operating handle 51 and the overcenter coil spring device 53 thus forms a mechanism similar to a pair of toggle links and an overcenter spring.

The circuit for the breaker extends from the left-hand end terminal 11 to the stationary contact 15, movable contact 43, switch arm 17, bimetallic trip element 21 and through the flexible shunt conductor 63 to the right-hand end terminal 13.

A U-shaped arc shield 89 is disposed in the arc chamber 25 in order to deionize and quickly extinguish the arc formed between the stationary and movable contact when the circuit is opened, and also to protect the side walls of the arc chamber from damage by the arc.

The operation of the circuit breaker is as follows. With the parts in the position shown in Fig. 1, let it be assumed that it is desired to manually open the circuit controlled by the breaker. To open the circuit, the operating handle 51 is moved in a clockwise direction from the closed circuit position shown in Fig. 1 to the open circuit position at the opposite end of the opening 71. During the first part of the clockwise rotation of the operating handle 51 about its pivot pin 67, the coil springs 79 and 81 are compressed until the pivot pin 77 of the upper spring end support crosses the line joining the center of the pin 67 and the point of engagement of the spring end support 85 with the cross-piece 87 of the actuating member 49. At this instant, the toggle formed by the depending portion 73 and the overcenter spring device 53 is in the equilibrium position. The instant that the pin 77 moves to the left of the line joining the pin 67 and the point of engagement of the end support 85 with the cross-piece 87, the handle 51 is automatically moved with a snap action to its open circuit position. After the pin 77 is moved to the left of the imaginary line mentioned, the force exerted by the springs 79 and 81 tending to hold the contact arm 17 in closed circuit position progressively decreases until it becomes less than the force exerted by the biasing spring 65. At this instant the line of action of the springs has moved to the left of a line joining the center of the pivot pin 41 and the cross-piece 87 so that the force exerted by the springs 79 and 81 and also the force exerted by the spring 65 moves the switch arm 17 in a clockwise direction about its pivot pin to its open circuit position with a snap action. In the open circuit position, the pin 77 occupies a position to the left of the center line joining the pins 67 and 41 at a perpendicular distance therefrom equal to the corresponding distance therefrom that the pin occupies in the closed circuit position of the operating handle.

In closing the circuit breaker substantially the reverse action takes place. To close the breaker, the operating handle 51 is moved from its open

circuit position in a counter-clockwise direction about its pivot pin 67 to the closed circuit position shown in Fig. 1. During movement of the operating handle to the closed circuit position, 5 the pivot pin 77 moves past the center line joining the pivot pin 67 and the cross-piece 87. After the pin 77 crosses this center line, the springs 79 and 81 move the handle 51 automatically and with a snap action to its closed circuit 10 position. At a certain point in the movement of the springs 79 and 81, their line of action moves to right of a line joining the center of the pivot pin 41 and the cross-piece 87 and the force exerted by these springs then moves the switch arm 15 17 in a counter-clockwise direction about the pin 41 to its closed circuit position with a snap action. The force exerted by the springs 79 and 81 is considerably greater than that exerted by the spring 65 and produces a large contact pressure 20 between the contacts 15 and 43 to insure a good electrical connection therebetween.

With the parts of the circuit breaker in the closed circuit position shown in Fig. 1, if an overload of predetermined magnitude and sufficient 25 duration occurs in the circuit controlled by the breaker, the overload current heats the bimetallic trip element 21 and causes the free end 59 thereof to disengage the cross-piece 61 of the actuating member 49. The disengagement of the 30 free end 59 of the bimetallic trip element 21 from the cross-piece 61 of the actuating member releases the switch arm 17 from its connection to the actuating member 49. Following the release 35 of the switch arm from its connection with the actuating member 49, the biasing spring 65 moves the switch arm 17 in a clockwise direction about its pivot pin 41 to the open circuit position, as shown in Fig. 3. The circuit controlled by the breaker is thus automatically opened in response to predetermined overload conditions.

40 To reset the breaker after a tripping operation has occurred, the operating handle is moved from the closed circuit position to the open circuit position, which causes the actuating member 49 to be rotated in a clockwise direction about its pivot pin 41 until the cross-piece 61 thereof reengages under the end 59 of the bimetallic trip element 21 after it has cooled and returned to normal position. After the breaker has thus 45 been reset, as described, the circuit breaker may be closed again by manually moving the operating handle 51 to its closed circuit position, since the engagement of the bimetallic trip element 21 with the cross-piece 61 of the actuating member 49 has reestablished the connection between the 50 switch arm 17 and the actuating member 49.

The trip characteristic of the circuit breaker 55 may be adjusted by means of an adjusting screw 91 which is threaded through the bimetallic element 21 and the resilient end portion 47 of the switch arm 17. The end of the screw 91 engages the solid wall of the notch 45 and by turning the screw 91 in a clockwise direction, the resilient end portion 47 is moved a small distance 60 to the right so as to increase the amount of overlap between the free end portion 59 of the trip element 21 and the cross-piece 61 of the actuating member 49. Increase in the amount of overlap between the free end 59 of the trip element 21 65 and the cross-piece 61 increases the value of overload current necessary to effect a tripping operation or increases the time interval between the occurrence of the overload and the tripping action on lower magnitude overloads.

70 The cover 9 is adapted to be removably

75 mounted on the base 7 by means of bolts (not shown) which pass through aligned openings 93 provided in the base 7 and cover 9. The removable mounting of the cover 9 and the vertical grooves 29 in the side walls of the cover 9 and base 7 for the reception of the pivot pins 67 and 41 provides a structure whereby the parts of the circuit breaker may be quickly and easily assembled or disassembled for adjustment, repair or replacement purposes.

10 In Fig. 4 is shown a modified form of circuit breaker embodying the features of my invention. In this form of the invention the structure of the end terminals, the stationary contact, the switch arm, the actuating member and the trip 15 element are identical to the corresponding parts of the embodiment shown in Figs. 1 and 2 and described in connection therewith. Consequently, the same reference characters have been used wherever applicable and only a brief 20 description of these parts will be given.

Referring to Fig. 4, the circuit breaker comprises, in general, an open-sided casing section 95, end terminals 11 and 13, a stationary or rupture contact 15, a co-operating movable switch 25 arm 17, a channel-shaped actuating member 49, a bimetallic trip element 21, an operating handle 97, and an overcenter spring 99.

The casing section 95 is formed of a single 30 piece of molded insulating material and has the same general cross-sectional outline as the casing formed by the base 7 and cover 9 in the modification shown in Figs. 1 and 2. The casing section 95 is open at one side and its side wall is provided with a projecting pivot stud 101 for 35 forming a pivot support for the switch arm 17 and the actuating member 49. A second pivot stud 103 projects from the side wall of the casing and forms a means for pivotally mounting the operating handle 97. Each of the end walls of 40 the casing section 95 is provided with a slot 105 for slidably receiving the end terminals 11 and 13. The top of the casing section 95 is provided with a recess 107 for the reception of the operating handle 97, and a portion of the handle 109 45 projects outwardly through the top of the recess 107.

In this modification of the invention, the switch arm 17 is normally connected to the channel-shaped actuating member 49 by means of the 50 bimetallic trip element 21 in the same manner as was described in connection with the embodiment shown in Figs. 1 and 2. The switch arm is biased to its open circuit position by means of a coil spring 65.

The operating means for moving the actuating member 49 and the normally connected switch member 17 to open and to closed circuit position 55 comprises the operating handle 97, and the overcenter spring 99. The operating handle 97 has a 60 notch 111 formed in the lower end thereof for receiving the upper end of the spring 99. The spring 99 is of the leaf type and has a reduced 65 lower end portion 113 which is adapted to pass through an opening 115 formed in the cross-piece 87 of the actuating member 49. The shoulders of the spring 99 formed by the reduced portion 113 thus pivotally engage the top of the cross-piece 89 to form a pivotal connection between the 70 spring 99 and the actuating member 49. The length of the spring 99 is greater than the distance between its point of engagement with the bottom of the notch 111 of the operating handle 97 and its point of engagement with the actuating 75

member 49, so that it is held in stressed or bowed condition as shown in Fig. 4.

All of the parts of the circuit breaker are adapted to be removably mounted in the open-sided casing section through the open side thereof. The end terminals 11 and 13 are adapted to be slid into the notches 105 formed in the end walls of the casing and are retained in operative position by means of the screws 33 and 37. The biasing spring 65, the switch arm 17, and the actuating member 49 are adapted to be inserted through the open side of the casing and mounted on the projecting pivot stud 101. The operating handle 97 is also adapted to be inserted through the open side of the casing section for mounting on the projecting pivot stud 103. The lower end of the over-center spring 99 is inserted through the open side of the casing section into the opening 115 in the cross-piece 87 of the operating member 49, and the spring is bowed and its upper end pushed into the notch 111 of the operating member 97. It will thus be seen that all of the parts of the circuit breaker may be readily and easily assembled or disassembled, through the open side of the casing section.

The operation of this modification of the invention is substantially similar to that of the embodiment shown in Figs. 1 and 2. With the parts in the closed circuit position, as shown in Fig. 4, let it be assumed that it is desired to open the circuit controlled by the breaker. To open the circuit, the operating handle 97 is moved in a clockwise direction about its pivot stud 103. At a certain point in the clockwise rotation of the operating handle, the leaf spring 99 snaps over-center to automatically move the handle 97 to its open circuit position and to rotate the actuating member 49 and normally connected switch member 17 in the clockwise direction about their pivot stud 101 to their open circuit position, with a snap action in substantially the same progressive manner as was described in connection with the embodiment shown in Figs. 1 through 3.

In closing the circuit breaker substantially the reverse action takes place. The operating handle is moved from the open circuit position in a counter-clockwise direction to the closed circuit position shown in Fig. 4. At a certain point in the movement of the operating handle the leaf spring 99 passes its point of equilibrium and snaps over-center to automatically move the operating handle 97 to its closed circuit position and to rotate the actuating member 49 and normally connected switch arm 17 in a counter-clockwise direction about the pivot stud 101 to their closed circuit position with a snap action in substantially the same progressive manner as was described in the operation of the embodiment shown in Figs. 1 through 3. The leaf spring 99 provides a means for securing quick make and quick break action during the manual operation of the circuit breaker. With the parts in the closed circuit position shown in Fig. 4, the endwise thrust or force exerted by the leaf spring 99 is sufficient to hold the switch arm 17 in closed circuit position and to provide a definite contact pressure between the movable contact and the stationary contact in spite of the biasing action of the spring 65 since the force exerted by the spring 99 is considerably greater than that exerted by the spring 65.

The tripping operation of this modification of the invention is identical with the tripping operation described in connection with the embodiment shown in Fig. 1. When an overload of pre-

determined magnitude and duration occurs in the circuit controlled by the breaker, the bimetallic trip element 21 flexes so as to disengage its end 59 from the cross-piece 61 of the actuating member 49 to release the switch arm 17 from the actuating member 49. When the switch arm 17 is released, the biasing spring 65 moves it to its open circuit position. To reset the circuit breaker after a tripping operation, the operating handle 97 is moved to the open circuit position which causes the actuating member 49 to rotate in the clockwise direction about the pivot pin 101 to effect reengagement of the free end of the bimetallic trip element 21 with the cross-piece 61 of the actuating member 49. The connection between the switch member 17 and the actuating member 49 is thus re-established and the circuit breaker may be manually closed by moving the operating handle to closed circuit position.

The casing section 95 of the circuit breaker is provided with a plurality of transverse openings 117. If the circuit breaker is to be used individually, a cover plate or cooperating casing section 119 is placed over the open side of the casing section 95 and secured thereto by means of bolts which pass through the openings 117. The cover plate section 119 acts to hold the parts in their mounted position within the casing and seals the casing against the entrance of dirt or moisture. As shown on the drawings, the joint or division plane between the two members or sections of the insulating housing is generally parallel with the plane of movement of the movable contact, which means that the two members or sections are separable sidewise. This is an important difference from the type of two-section casing shown in Figs. 1, 2 and 3, because all of the parts may be assembled through the open side of one casing section, and also because it provides maximum visibility and accessibility of the parts for purposes of inspection and adjustment after the breaker is completely assembled and before the covering member of the casing is put in place. If desired, a number of the circuit breaker units shown in Fig. 4 may be mounted side-by-side in a group, as illustrated in Fig. 5. In such case, elongated bolts pass through the aligned openings 117 of the units and secure the units together and the cover plate 119 over the open side of the end unit. When the units are secured together to form a group, as shown in Fig. 5, the side wall of each unit acts to close the open side of the adjacent unit, and to retain the parts thereof in their mounted position. The grouped circuit breaker units may be used as a multi-pole circuit breaker or as a load center device.

It will thus be seen that I have provided an efficient and simple circuit breaker structure that utilizes a minimum number of parts and that can be manufactured at a low cost. The circuit breaker structure also embodies the desirable quick make-and-break action and may be easily assembled or disassembled for adjustment, repair or replacement purposes.

While I have shown and described several embodiments of my invention in accordance with the patent statutes, it is obvious that various changes may be made in the structural details without departing from the spirit of the invention. I desire, therefore, that the invention be limited only by the reasonable construction of the language of the appended claims and by the prior art.

I claim as my invention:

1. In a circuit breaker, a movable switch arm 75

biased at all times to open circuit position, an independently movable actuating member, means including a current-responsive device for normally connecting said switch arm to said actuating member for movement thereby, operating means including an operating handle mounted for movement relative to said actuating member, and an overcenter spring connecting said handle to said actuating member for moving said actuating member and normally connected switch arm to open and to closed circuit position with a snap action to open and to close the circuit, said current-responsive device being operable in response to predetermined conditions to release said switch arm from said actuating member to permit said switch arm to move to open circuit position independently of the position of said handle.

2. In a circuit breaker, a movable switch arm having a spring biasing it to open circuit position, an independently movable actuating member, means including a bimetallic element for normally connecting said switch arm to said member for movement thereby, operating means including an operating handle mounted for movement relative to said actuating member, and a second spring between said handle and said member for moving said member and normally connected switch arm to open and to closed circuit position with a snap action, said bimetallic element being operable in response to predetermined conditions to release said arm from said member to allow said arm to be moved by its spring to open circuit position independently of said second spring.

3. In a circuit breaker, a switch arm mounted for pivotal movement about a fixed axis only, means biasing said arm to open circuit position, an actuating member pivoted to move only about the same axis as said arm, means including a bimetallic element connected in circuit with said switch arm for normally connecting said arm to said member for movement therewith, operating means including an operating handle mounted for movement relative to said actuating member, and an overcenter spring for moving said member and connected switch arm to open and to closed circuit position with a snap action, said bimetallic element being operable in response to abnormal circuit conditions to effect disconnection of said arm from said member to allow said biasing means to move said arm to open circuit position independently of the position of said operating means.

4. In a circuit breaker, a pivotally mounted switch member, means biasing said member to open circuit position, a movable actuating member, means including a bimetallic element having one end secured to said switch member for normally connecting said members for movement together, operating means including an operating member mounted for movement relative to said actuating member, and an overcenter spring for moving said normally connected members to open or to closed circuit position with a snap action even if the said operating member is moved slowly throughout its range of movement, said bimetallic element being operable in response to abnormal conditions to release said switch member from said actuating member to allow the first said biasing means to move said switch member to open circuit position irrespective of the position of said operating means and without requiring movement of said actuating member.

5. In a circuit breaker, a switch member mounted for pivotal movement about a single

fixed axis and biased to open circuit position, an actuating member pivoted for movement only about the same axis as said switch member, means including a bimetallic strip having one end secured to one of said members, for normally connecting said members for movement together, operating means for moving said normally connected members to open and to closed circuit position with a snap action, said bimetallic strip being operable in response to predetermined conditions to release said switch member from said actuating member to allow said switch member to move to open circuit position.

6. In a circuit breaker, a switch member mounted for pivotal movement about a single fixed axis, means biasing said member to open circuit position, a movable actuating member having a single fixed axis, means including a bimetallic element connected in the circuit controlled by the breaker and having one end secured to one of said members for normally connecting said members for movement together, a manually operable snap acting mechanism for moving said normally connected members to open and to closed circuit position with a snap action, said mechanism causing said switch member to remain in either position during operation of the mechanism until the mechanism snaps, said bimetallic element being flexed in response to predetermined overload conditions to disengage its free end from said other member for disconnecting said members to allow said biasing means to move said switch member to open circuit position.

7. In a circuit breaker, a switch member mounted for pivotal movement about a single fixed axis, means biasing said member to open circuit position, a movable actuating member, means including a bimetallic element connected in the circuit controlled by the breaker and having one end secured to one of said members for normally connecting said members for movement together, a snap acting mechanism including a movable operating handle for moving said normally connected members to open and closed circuit position with a snap action irrespective of how slowly said operating handle is moved throughout its range of movement, said bimetallic element being flexed in response to predetermined overload conditions to disconnect said members to allow said biasing means to move said switch member to open circuit position even though said actuating member may be prevented from moving.

8. In a circuit breaker, a base, a switch arm pivotally mounted on said base and biased to open circuit position, an actuating member pivotally mounted on said base about the same axis as said arm, means including an electro-responsive device for normally connecting said arm to said member for movement therewith, operating means comprising a pivotally mounted toggle-type operating handle, and a compression spring having one end pivotally connected to said handle and its other end pivotally engaging said actuating member, for moving said member and normally connected arm to open or to closed circuit position with a snap action, a cover mounted on said base provided with an opening through which projects a portion of said handle, said electro-responsive device being operable in response to abnormal overload conditions to disconnect said arm from said member to allow said arm to move to open circuit position irrespective of the position of said operating handle and spring.

9. In a circuit breaker, a chambered base, a pivot pin disposed transversely between the side walls of said base, a switch arm pivotally supported by said pin and biased to open circuit position, an actuating member pivotally supported by said pin, means including an electro-responsive device for normally connecting said arm to said member for movement therewith, a cooperating chambered cover for said base, a toggle type operating handle pivotally supported between the side walls of said cover about an axis parallel to and substantially above that of said pivot pin, said handle having its upper end extending through an opening provided therefor in the top 10 of said cover, an overcenter compression spring having one end pivotally coupled to the lower end of said handle and its lower end pivotally coupled to said actuating member, said handle being movable to an open or to a closed circuit 15 position to move said member and normally connected arm to an open or to a closed circuit position with a snap action, said electro-responsive device being operable in response to predetermined conditions to disconnect said arm from 20 said member to allow said arm to move to the open circuit position irrespective of the position of said handle.

10. In a circuit breaker a pivotally mounted switch arm, means biasing said arm to the open 25 circuit position, an actuating member pivoted about the same axis as said arm, means including a bimetallic element for normally connecting said arm and said member for movement together, operating means including a pivotally mounted 30 operating handle and a stressed leaf spring between said handle and said actuating member for moving said member and normally connected switch arm to open and to closed circuit position with a snap action, said bimetallic element being 35 operable in response to predetermined conditions to disconnect said arm from said member to allow said biasing means to move said arm to open circuit position.

11. In a circuit breaker, a pivotally mounted 40 switch arm, an actuating member pivoted about the same axis as said switch arm, means including a bimetallic element for normally connecting said arm to said member for movement therewith, operating means comprising a pivotally mounted operating handle having a bifurcated 45 end portion, a leaf spring having one end engaged in the bifurcation of said handle and its other end engaging a point of said member between the pivot axis thereof and the pivot axis of 50 said handle, the length of said spring being greater than the distance between its points of engagement with said handle and said member so that it is held in stressed bowed condition, said operating handle being movable to open or to 55 closed circuit position to cause said spring to move said actuating member and normally connected arm to open or to closed circuit position with a snap action, said bimetallic element being 60 operable in response to a predetermined condition to release said arm from its connection with 65 said member.

12. In combination, a plurality of individual 70 circuit breaker units, each of said units comprising an open-sided casing, end terminals for connecting the unit in an electrical circuit, contact means, operating means for said contact means, and means for removably mounting said end terminals, said contact means and said operating means in said casing through the open side thereof, means for securing said units together so that 75

the side wall of each unit, but one, closes the open side of the adjacent unit and retains the parts thereof in mounted position.

13. The combination of a plurality of individual circuit breaker units, each of said units comprising an open-sided casing, a stationary contact, a cooperating movable switch arm, operating means for moving said switch arm to open and to closed circuit position, a trip device for causing said switch arm to move to open circuit 10 position in response to predetermined overload conditions, end terminals for connecting the unit in an electrical circuit, and means for removably mounting said parts in said casing through the open side thereof, means for securing said units 15 together, so that the side wall of each unit closes the open side of the adjacent unit and retains the parts thereof in mounted position, and a cover plate for the open side of one end unit.

14. A circuit breaker unit comprising a casing 20 of insulating material, a pivotally mounted switch member, means biasing said member to open circuit position, an actuating member pivoted about the same axis as said switch member, means including an electro-responsive device for normally 25 connecting said members for movement together, operating means including an operating member mounted for movement relative to said actuating member, and an overcenter spring for moving said actuating member and the normally connected 30 switch member to open and to closed circuit position with a snap action, said electro-responsive device being operable in response to predetermined conditions to effect disconnection of 35 said switch member from said actuating member to allow said biasing means to move said switch member to open circuit position, said operating member being pivotally mounted in bearings provided in the insulating material of 40 said casing.

15. A circuit breaker unit comprising, in combination, an open-sided casing, a stationary contact, a cooperating movable switch member, operating means for moving said switch member to open and to closed circuit position, a trip device 45 operable in response to predetermined conditions to cause said switch member to move to open circuit position independently of said operating means, terminals for connecting said unit in an electrical circuit, said casing being provided with 50 means for slidably receiving said abovementioned parts whereby said parts are removably mounted in said casing through the open side of said casing.

16. In a circuit breaker, a chambered base, a 55 cooperating chambered cover, said base and cover forming a split casing, the side walls of said base and cover being provided with oppositely disposed aligned grooves, a contact controlling arm mounted on a transverse pivot pin 60 which is removably mounted in the grooves of said base, the ends of said pin being rotatably supported by the bottom ends of said grooves, operating means for moving said arm about its pivot pin to open and to closed circuit position 65 with a snap action to open and to close the circuit comprising a toggle type operating handle having a portion adapted to project through an opening in the top of said cover and a transverse pivot pin, an overcenter spring connected to said 70 handle and to said arm at a point above the pivot pin of said arm, the pivot pin of said handle being removably mounted in the grooves of said cover so that its ends are rotatably supported against the top ends of said grooves, said spring 75

being held in compressively stressed condition between said handle and arm to hold the ends of said pivot pins against the ends of said grooves.

17. In a circuit breaker, a contact arm mounted

- 5 for pivotal movement about a fixed axis, means biasing said arm to open position, an independently movable actuating member, means including an electro-responsive device for normally connecting said contact arm to said actuating member for movement thereby, operating means including an operating member mounted for movement relative to said actuating member, and an overcenter spring for moving said actuating member and normally connected contact arm to 10 open and to closed position with a snap action, said electro-responsive device being operable in response to predetermined conditions to effect release of said contact arm from said actuating member to permit movement of said contact arm 15 to open position by the first said biasing means independently of said overcenter spring.

18. In a circuit breaker, a pivotally mounted switch member, means biasing said member to the open circuit position, a movable actuating mem-

- 25 ber, means including a bimetallic element for normally connecting said switch member to said actuating member for movement thereby, operating means including a manually operable operating handle for moving said normally connected members to open and to closed circuit position with a snap action even though said handle is moved slowly throughout its range of movement, said bimetallic element being operable in response to 30 predetermined conditions to release said switch member from said actuating member to permit said switch member to be moved to open position by the first said biasing means irrespective of the position of said handle and independently of said overcenter spring.

40 19. The combination in an automatic circuit breaker, of a rupture contact, a movable contact member provided with a contact engageable with the rupture contact, a manually movable operating member, mechanism including means opera-

45 tive upon movement of the operating member to cause movement of the contact member and including an element adapted to cause opening of the contact member independent of any control of the operating member upon the attainment of abnormal current conditions in the circuit, and a 50 two-piece insulating housing enclosing all of the aforesaid parts other than the manually engageable portion of the operating member and having the division plane between the two pieces parallel

55 with the direction of movement of the contact member, the said housing having means for fixing the path of movement of the contact member and for pivotally supporting the operating member, and the said housing being free from positive 60 connection with any substantially movable parts so that when the two pieces of the housing are assembled the said parts are movably held between them and so that when the sections are separated the said movable parts are readily separable therefrom.

65 20. In an automatic circuit breaker, the combination of a rupture contact, a contact member movable and provided with a contact surface engageable with the rupture contact, a manually

70 movable operating member, mechanism including means operative upon movement of the operating member to cause movement of the movable contact member and including an element adapted to cause opening of the movable contact member 75 independent of the operating member upon the

attainment of abnormal current conditions in the circuit, and a housing enclosing all of the aforesaid parts other than the manually engageable portion of the operating member and comprising two pieces of insulating material having 5 the joint between them generally parallel with the plane of movement of the movable contact member, the said housing having a plurality of means each serving as the supporting and movement defining means for one of the aforesaid 10 parts and said housing being free from positive connection with any substantially movable parts so that it is only when the two pieces are assembled together that the said substantially movable parts are positively held in operative relation. 15

21. In an automatic circuit breaker, the combination of a rupture contact, a contact member movable and provided with a contact surface engageable with the rupture contact, a manually movable pivoted operating member, mechanism 20 including means operative upon movement of the operating member to cause movement of the movable contact member and including an element movable to initiate opening movement of the movable contact member independently of the 25 operating member upon the attainment of abnormal current conditions in the circuit, and an insulating housing enclosing all of the aforesaid parts other than the manually engageable portion of the operating member and comprising two 30 members having the joint between them extending generally in the same direction as the plane of movement of the movable contact member, at least one of the said insulating housing members serving as the frame of the circuit breaker and 35 having means movably supporting the movable contact member and the pivot of the operating member without said movable contact member and said operating member being positively fastened to said housing member, and the said housing member receiving said movable parts through its open side at said joint so that when the housing members are assembled the said parts are held between them. 40

22. In an automatic circuit breaker, the combination of a rupture contact, a contact member 45 movable and carrying a contact surface engageable with the rupture contact, a manually movable operating member, mechanism operatively connecting the operating member with the movable contact member and including an element movable to permit opening movement of the movable contact member independently of the operating member upon the attainment of abnormal current conditions in the circuit, and an insu-

50 lating housing enclosing all of the aforesaid parts other than the manually engageable portion of the operating member and comprising two members of insulating material having the joint between them generally parallel with the plane of 55 movement of the movable contact member, and at least one of the said insulating members serving as at least part of an insulating frame individually supporting the movable contact member and the operating member without being positively fastened thereto. 60

23. In an automatic circuit breaker, the combination of a rupture contact, a contact member movable and provided with a contact surface engageable with the rupture contact, a manually 70 movable operating member, mechanism including means for operatively connecting the operating member with the movable contact member and said mechanism being movable to permit opening movement of the movable contact member inde- 75

- pendently of the operating member upon the attainment of predetermined current conditions in the circuit, an insulating housing enclosing all of the aforesaid parts other than the manually engageable portion of the operating member and comprising two parts having the joint between them generally parallel with the plane of movement of the movable contact member, and at least one of said parts of the housing having means for slidably receiving said movable contact member, said operating member and said mechanism, and said movable contact member and said operating member being supported on said part of the housing by said means for slidably receiving them without being fixedly secured thereto.
24. In an automatic circuit breaker, the combination of a rupture contact, a movable contact member provided with a contact surface engageable with the rupture contact, a manually movable operating member, mechanism operatively connecting the operating member with the movable contact member, said mechanism permitting opening movement of the movable contact member independently of the operating member upon the attainment of abnormal current conditions in the circuit, a pair of terminal members, one of said terminal members carrying said rupture contact and the other of said terminal members being electrically connected to said movable contact member, an insulating housing enclosing all of the aforesaid parts except the manually engageable portion of the operating member and the terminal ends of said terminal members, said housing comprising two members having the joint between them generally parallel with the direction of movement of the contact member, at least one of said housing members serving as an insulating frame and having an open side, a closed side and means for receiving each of said parts through its open side, and said housing members having means serving to individually support said operating member and said movable contact member in position but having only readily detachable connection therewith.
25. The combination in an automatic circuit breaker, of a rupture contact, a movable contact carrying member provided with a contact engageable with the rupture contact, a manually movable operating member, mechanism normally operatively connecting the operating member with the contact carrying member and including a bimetallic member connected at one end to and movable with the movable contact and an actuating member connectable to the movable contact carrying member and movable upon movement of said operating member to normally actuate said movable contact, said actuating member being normally latched by the other end of said bimetallic member and being releasable from the bimetallic member upon the occurrence of a predetermined condition to permit opening of said movable contact independently of the said operating member, a pair of terminal members, one of said terminal members carrying said rupture contact and the other of said terminal members being connected by a flexible shunt to said other end of the bimetallic member, a two-piece insulating housing enclosing all of the aforesaid parts other than the manually engageable portion of the operating member and the terminal ends of said terminal members, the joint between said two pieces of the housing extending generally parallel with the direction of movement of the contact member, and at least one of said pieces of the housing serving as at least part of an insulating frame and having means for receiving the connected unit including said movable contact carrying member, said actuating member, said bimetallic member and the terminal member connected thereto by the flexible shunt, and said insulating frame also having means for separately receiving and supporting said operating member and the terminal member carrying the rupture contact, and said movable contact carrying member, said actuating member, said bimetallic member and said operating member all being free of positive connection with either piece of the insulated frame.
26. The combination in an automatic circuit breaker, of a stationary rupture contact, a movable contact member provided with a contact engageable with the rupture contact, a manually movable operating member, mechanism operatively connecting the operating member with the contact member and including an element adapted to release the contact member from the control of the operating member upon the attainment of abnormal current conditions in the circuit, a two-section insulating housing enclosing all of the aforesaid parts other than the manually engageable portion of the operating member and having the division plane between the two sections parallel with the direction of movement of the contact member, the said housing sections serving as the sole means for supporting the contact member for movement and for pivotally supporting the operating member and the said sections being free from positive connection with any movable parts so that when the sections are assembled the said parts are movably held between them and so that when the sections are separated the said parts are readily separable therefrom, and a metallic element carrying the rupture contact and connected to at least one of the housing sections.
27. A circuit breaker unit comprising, in combination, an open-sided casing, a stationary contact, a cooperating movable switch member, operating means for moving said switch member to open and to closed circuit position, a trip device operable in response to predetermined conditions to cause said switch member to move to open circuit position independently of said operating means, terminals for connecting said unit in an electrical circuit, said casing being provided with means for slidably receiving said above-mentioned parts whereby said parts are removably mounted in said casing through the open side of said casing, a second casing member for completing the casing and holding the above-mentioned parts therewithin, and the joint in the completed casing extending in the same general direction as the plane of movement of said movable switch member.
28. A circuit breaker comprising, in combination, an open-sided casing member, a contact, a switch member having a contact surface movable to engage and disengage the first said contact, operating means including a handle for moving said switch member to engaged and disengaged positions, a trip element operable in response to predetermined conditions to cause said switch member to move to disengaged position independently of the position in which said handle may be held, a second casing member cooperating with the first said casing member for enclosing all of the aforesaid parts other than the manually engageable portion of the handle, said casing members being separable

from each other in the direction perpendicular to the plane of movement of said switch member and at least one of them serving as an insulating frame having separate means for retaining said contact, said switch member and said handle without being securely fastened thereto.

29. A circuit breaker comprising, in combination, an open-sided casing member of insulating material, a first contact, a cooperating movable switch member provided with a second contact engageable with said first contact, operating means including a manually operable member for moving said switch member to open and to closed circuit position, a trip element operable in response to predetermined conditions to initiate movement of said switch member to open circuit position irrespective of the position in which said manually operable member may be held, a second casing member of insulating material engaging the first said casing member at a joint extending in the same general direction as the plane of movement of said switch member, the first said open-sided casing member receiving at least some of the aforesaid parts through its open side, and said casing members forming the enclosure for the circuit breaker and at least one of said casing members also forming the frame of the circuit breaker having means by which said first contact, said switch member and said manually operable member are individually mounted by being merely placed in position in engagement with said mounting means.

30. In a circuit breaker, an open-sided casing member of insulating material, a terminal strip having a contact thereon, a movable switch member having a contact thereon for engaging the contact on the terminal strip, operating means including a manually operable member for moving said switch member to open and to closed circuit position and a bimetallic element operable in response to predetermined conditions to initiate movement of said switch member to open circuit position irrespective of the position in which said manually operable member may be held, a second terminal strip having the bimetallic member connected in series therewith, a second casing member of insulating material, one of said casing members having means for slidably receiving said movable switch member and said operating means, said casing members having their meeting edges so positioned as to be assembled together by movement toward each other in a direction perpendicular to the plane of movement of said switch member, said casing members of insulating material forming the frame of the circuit breaker and having both said switch member and said manually operable member individually supported thereon for operative movement and being readily separable therefrom, and said casing members enclosing all of the aforesaid parts except the terminal ends of said terminal strips and one end of said manually operable member.

31. In a circuit breaker, an open-sided casing member of insulating material, a terminal strip having a contact mounted thereon, a movable switch member having a contact thereon for engaging the contact on the terminal strip, operating means including a manually operable member, and a bimetallic member connected at one end to said switch member to move therewith and electrically connected in series with the contact on the switch member, said bimetallic mem-

ber having its other end normally in latching engagement with said actuating member to cause said switch member to move upon movement of said operating member and said bimetallic member being releasable from said actuating member upon the occurrence of a predetermined abnormal condition to permit opening of the switch member independently of the position of said manually operable member, a second terminal strip having a flexible conductor secured at one end thereto for connecting said bimetallic member in series therewith, a second casing member of insulating material cooperating with the first said casing member for forming a divided enclosure for all of the aforesaid parts other than the operating end of said manually operable member and the terminal ends of said terminal strips with the joint between said casing members extending in the same general direction as the plane of movement of said switch member, and at least one of said casing members acting as an insulating frame for the circuit breaker and supporting at least all of the aforesaid parts other than said terminal strips in operative relation without being separately fastened thereto.

32. A circuit breaker unit comprising, in combination, an open-sided casing, a contact, a cooperating movable switch member, operating means for moving said switch member to open and to closed circuit position, a trip device operable in response to predetermined conditions to cause said switch member to move to open circuit position independently of said operating means, terminals for connecting said unit in an electrical circuit said casing being provided with means for slidably receiving at least a majority of the above-mentioned parts through the open side of said casing, and a closure member having a substantially plane surface on one side engaging said open-sided casing with said plane surface lying at one side of the aforesaid parts and generally parallel to the plane of movement of said switch member, said closure member being the only means for securing a majority of the aforesaid parts in position with said means for slidably receiving them in the open-sided casing.

33. In an automatic circuit breaker, the combination of a pair of terminal members, a first contact electrically connected to one of said terminal members, a movable contact carrying member provided with a contact surface engageable with the said first contact, a manually movable operating member, means for operatively connecting the manually movable operating member to the movable contact carrying member with a readily separable connection between said means and said manually movable operating member, said means being movable to permit opening movement of the movable contact carrying member independently of the manually movable operating member upon the attainment of predetermined current conditions in the circuit and including a bimetallic element mounted and electrically connected at one end on said movable contact carrying member and having a flexible conductor connecting its other end directly to the other of said terminals, an insulating housing enclosing all of the aforesaid parts other than the manually engageable portion of the manually movable operating member and the terminal ends of said terminal members, said insulating housing comprising two parts having the joint between them extending in the same general direction as the plane of movement of the movable contact carrying member and at least one of said parts

of the housing having means for slidably receiving the connected unit including the first said contact and terminal, the unit including said movable contact carrying member, said bimetallic member, said flexible conductor and said other terminal, and the unit including said manually movable operating member, and said movable contact carrying member and said manually movable operating member being secured to said one part of the housing only by being slipped into engagement with said means for slidably receiving them and by securing the two parts of the housing together.

34. In a circuit interrupter, a first assembly unit including a terminal strip having means for securing a conductor thereto adjacent one end thereof and a contact surface adjacent the other end thereof, a second assembly unit including a manually movable operating member, a third assembly unit including a movable contact carrying member, a bimetallic element mounted and electrically connected at one end on said movable contact carrying member and a second terminal having means for securing a conductor thereto at one end and connected by a flexible portion to the other end of said bimetallic element, and a housing in which said three assembly units are mounted in operative relation without being fixedly secured to each other and with said contact carrying member movable in response to movement of said manually movable operating member to both make and break the circuit and movable upon flexing of said bimetallic element to break the circuit

irrespective of the position in which said manually movable operating member is held, said housing including two members of insulating material having means for slidably receiving said three assembly units with the joint between the two members extending generally parallel to the plane of movement of said contact carrying member.

35. A circuit breaker unit comprising, in combination, an open-sided casing, a stationary contact, a cooperating movable switch member, operating means for moving said switch member to open and to closed circuit position, said operating means including a pivoted handle member and an over-center spring having its line of action movable across the pivot of the handle member and acting when in closed position to bias said switch member into engagement with said stationary contact and acting when in open position to bias said switch member to open position, a trip device operable in response to predetermined conditions to cause said switch member to move to open circuit position independently of said operating means, terminals for connecting said unit in an electrical circuit, said casing being provided with means for slidably receiving said above-mentioned parts whereby said parts are removably mounted in said casing through the open side of said casing, a second casing member for completing the casing and holding the above-mentioned parts therewithin, and the joint in the completed casing extending in the same general direction as the plane of movement of said movable switch member.

OLIVER S. JENNINGS.
